METHOD OF AND APPARATUS FOR
CONDITIONING AIR

William R. Zuhlke, Yonkers, N. Y., assignor, by
mesne assignments, to American Radiator &
Standard Sanitary Corporation, New York,
N. Y., a corporation of Delaware

Application October 24, 1936, Serial No. 107,376

12 Claims. (Cl. 183—4)

The general object of my invention is to provide an improved method of and apparatus for conditioning air, and particularly air for ventilating rooms or spaces used for human occupancy.

5 My invention is characterized by, and comprises, an improved method of, and apparatus for reducing the moisture content of, or dehumidifying air, and in some cases, its dehumidification is the only significant change in the condition of 10 the air effected by the use of my invention. However, my method of dehumidification involves an initial heating and subsequent cooling of the air, and the air cooling operation may advantageously be carried out in some cases, so as to make the 15 delivery temperature of the conditioned air less than the initial temperature of the air conditioned.

In conditioning air in accordance with the 20 present invention, I eliminate moisture from the air by bringing it into contact with some material such as silica-gel or calcium chloride which in a dried, or activated, condition is adapted to absorb a large amount of moisture from air brought into contact with the material, and which 25 after having its moisture absorbing capacity reduced by absorbed moisture which it holds, can have that capacity restored or increased, by a reactivation or regeneration treatment, which I effect by bringing into contact with the material, 30 hot air admixed with products of combustion of fuel burned to heat the air. The words absorb and absorption, as herein are intended to generically include the action specifically designated by the words adsorb and adsorption.

35 Heretofore various proposals have been made for the use of absorbing material of the character above mentioned, to dehumidify air and for the regeneration or reactivation of the material, from time to time, by bringing hot gases into contact 40 with the material.

45 My invention is characterized, however, by novelty in the means for and method of carrying out and relating the dehumidification and regeneration steps or stages, by which the moisture absorbing material is alternately used as a dehumidifying agent and is subjected to a regeneration or reactivation action.

50 My invention takes into account and makes use of the fact that room atmosphere conditions suitable for the comfort and health of the room occupants may be maintained by the intermittent supply of an adequate supply of fresh air to the room, and that if the periods during which air is supplied are suitably long, and alternate with 55 periods suitably short in which the supply of fresh

air is interrupted, the general ventilation and conditioning effect will be practically equivalent to that obtainable by the continuous supply of substantially the same amount of fresh air to the room. While the precise duration of the successive dehumidifying and regenerating stages of the cyclic operation which I provide, may vary with conditions, I note, by way of example, that a preferred form of apparatus for the practice of my invention, hereinafter described in detail, was 10 designed, and is adapted, for successive operation cycles, each comprising a 40 minute dehumidification stage or period, and a regeneration stage or period of from 13 to 20 minutes, depending on the amount of moisture absorbed during the 15 previous dehumidification period.

My invention, in its preferred form, is also characterized by novel means and steps provided to permit or facilitate the regeneration of the 20 moisture absorbing material, in a period approximately only one-third to one-half as long as the immediately preceding 40 minute dehumidification period.

In the preferred form of my invention I continuously move air, drawn directly from the atmosphere or other source of air to be conditioned, 25 into contact with the moisture absorbing material by which the air is dehumidified. During the dehumidification stage or period of each cycle, the air after passing out of contact with the moisture absorbing material, is subjected to a cooling 30 action to suitably lower the temperature of the air, which is raised while in contact with said material, by the addition to the air of sensible heat corresponding in amount to the latent heat 35 of evaporation of the moisture absorbed from the air by the material. During each regeneration, or reactivation, period or stage, the air is subjected to a heating action, suitably diminishing the relative humidity of the air, prior to the 40 passage of the air into contact with the absorbing material then regenerated or reactivated, and the air then passing out of the contact with the absorbing material, and carrying with it the moisture which it drives out of that material, is 45 diverted from the air cooling means used in the dehumidification stage and from the room or rooms ventilated, and is ordinarily discharged to waste.

The capacity for the regeneration of the material in approximately one-third to one-half of the time in which the material is used in dehumidifying ventilation air, is made practically possible in accordance with the present invention, by the use of simple and effective means for

heating the regeneration air approximately to the maximum temperature to which the absorbing material can be safely and economically subjected, and by disposing the moisture absorbing material relative to the path of air flow, so that in each dehumidification stage, the air passes in series through different portions of the material, while during each regeneration stage, different portions of the regenerating air passes in parallel 10 through the said different portions of the material.

For the practice of my invention I have devised a novel air conditioning apparatus unit of such character that it may be located in the 15 cellar or furnace room of an ordinary dwelling house of moderate size, and used in conditioning the air for ventilating some or all of the various rooms of the house. Said unit is adapted, however, for use with no significant change, except 20 in its dimensions, to provide conditioned air in larger amounts as required, for example, in the ventilation of office buildings, and of restaurants, theatres, and other large assembly rooms.

The improved unit in its preferred form is 25 especially adapted for domestic use and without requiring skilled attendance, by the mechanically simple and reliable character of the provisions for carrying out, and for automatically repeating the dehumidification and regeneration actions at 30 regular intervals.

The air cooling action to which the dehumidified air is subjected, may be effected by mechanical refrigeration means, by the use of cooling water drawn from city water supply mains 35 or other available source of cooling water, and by other means, and the character of the cooling means desirably employed in different installations, will ordinarily depend on cost and convenience considerations which will vary in 40 different installations. Wherever it is especially desirable, or the cost of the additional cooling required is not economically objectionable, the cooling action may be carried out so as to make the delivery temperature of the conditioned air 45 appreciably lower than the temperature of air supplied for conditioning. For ordinary ventilation purposes, in localities and under conditions in which I anticipate that the greatest practical use of the invention will be made, practically effective and satisfactory air conditioned results are obtainable without any significant reduction 50 in the temperature of the conditioned air below the prevailing atmospheric temperature, since, for example, air at a temperature as high as 55 85 or 90° F., in ordinary rooms, does not seriously inconvenience or give discomfort to the occupants of the room, provided the humidity of the air is suitably low. For such installations, and particularly where it is not convenient or too expensive 60 to cool the air by other means, I advantageously cool the air by an evaporative action, and the air cooler in a desirable form of my unit illustrated herein, includes a heat exchanger comprising 65 passages for the air to be cooled, which are in good heat transfer relation with passages through which I pass atmospheric air after spraying water into that air.

With such evaporative cooling, it is practically possible to reduce the temperature of the conditioned air appreciably below the atmospheric dry bulb temperature.

In addition to the general features mentioned above, my improved apparatus in preferred forms, comprises various novel features of construction and arrangement. While the various

features of novelty which characterize the invention are pointed out with particularity in the claims annexed to and forming a part of this specification, for a better understanding of the invention and its advantages, reference may be had to the accompanying drawings and descriptive matter in which I have illustrated and described a preferred embodiment of my invention.

Of the drawings, Fig. 1 is a sectional elevation 10 of a conditioning unit constituting one embodiment of the invention, the section being taken on the broken line 4—4 of Fig. 5;

Fig. 2 is a perspective view of the unit shown 15 in Fig. 1;

Fig. 3 is a section of an air cooler portion of the unit shown in Figs. 1 and 2, the right hand portion of the section being taken on the line 3a—3a, and the left hand portion on the line 3b—3b of Fig. 1;

Fig. 4 is a section on the broken line 4—4 of Fig. 3;

Fig. 5 is a plan section on the line 5—5 of Fig. 1;

Fig. 6 is a plan section on the line 6—6 of Fig. 1;

Fig. 7 is an elevation in section on the line 7—7 of Fig. 1;

Fig. 8 is an elevation in section on the broken line 8—8 of Fig. 6; and

Fig. 9 is a diagrammatic representation of automatic control means.

The air conditioning unit shown in Figs. 1 to 7, comprises an insulated housing or casing 1, provided at its top with an inlet 2 for air to be conditioned, a conditioned air outlet 3, and a waste outlet 4, through which moisture laden air mixed with products of combustion is discharged during the regeneration stage of the operating cycle, and through which warm humid air, used in cooling the conditioned air, is discharged during the dehumidification stage of operation.

The inlet 2 for air to be conditioned, opens into a plenum space or chamber 5, within the housing 1, from which, during the air conditioning stage 45 of the operating cycle, the air to be conditioned is moved by a blower or fan 6 through a duct 7 into a chamber 8. The latter encloses air heating apparatus, collectively designated 9, and hereinafter described in detail, which is used in the regeneration stage, but is inoperative during the air conditioning stage of the operating cycle. The chamber 8 is shown as above and opening through a bottom outlet part 10 into, a chamber 11. The latter is surrounded by a pervious wall 50 including moisture absorbing material 12. The air passes from the chamber 11 through said pervious wall into a surrounding space 13, enclosed by a casing or shell 14.

The pervious wall, space 13 and shell 14 are extended downwardly so that their lower portions surround a chamber 15 directly beneath the space 11 and separated from the latter by a partition 16 formed with a large central port, which is closed by a damper or valve 17 during the air conditioning stage. The air received in the space 13 from the chamber 11 during the air conditioned stage, passes again through the pervious wall including the water absorbing material 12, 70 into the chamber 15. The latter is provided at its bottom with an outlet port 18 which is open during the air conditioning stage, but is closed by a damper or valve 19, during the regeneration stage. The port 18 opens into one end of a con- 75

duit 20, which has a top wall outlet 21 at its other end, opening to the conditioned air passages 23 of an air cooler 22, through which the air passes upward to the conditioned air outlet 3.

As hereinafter explained in detail, the air cooler 22 is a channelled structure including passages 24, separate from the conditioned air passages 23, for the flow of the cooling agent. That agent in the unit form shown in Figs. 1 to 7, is air drawn from the plenum chamber 5 through an inlet 25, into an air humidifying chamber 26 having an upper portion extending through an opening in the top wall of the housing, and into which water is sprayed by nozzles 27. The chamber 26 has an outlet 28 communicating with the upper ends of the cooling agent passages 24 of the air cooler 22, at the top of the latter. The last mentioned passages communicate at the bottom of the air cooler with a duct 29 connected by a conduit 30 to the inlet of a fan or blower 31, employed to move air from the chamber 5 through the cooling fluid passages 24 of the air cooler 22, and which delivers that air through a discharge conduit 32 opening into a waste conduit or chamber 33 beneath, and opening directly to, the waste outlet 4. The chamber or conduit portion 33 is provided at its bottom with a port 34 which is closed during the air conditioning stage of the cycle by a valve or damper 35.

During the air conditioning stage of the cycle of operation of the unit, air to be conditioned flows continuously from the inlet 2, through the chamber 5, fan or blower 6, duct 7, chamber 8, chamber 11, chamber 13, chamber 15, port 18, duct 20, and the conditioned air passages 23 of air cooler 22, to the conditioned air outlet 3. As the air passes from the chamber 11 into the chamber 13, some of its moisture is absorbed as it passes through the upper portion of the bed of absorbing material 12 then traversed, and as the air passes from the chamber 13 into the chamber 15, the lower portion of the bed of material 12, then traversed, absorbs the remainder of the moisture eliminated from the conditioned air in the unit.

With the chambers 11 and 15 symmetrically disposed and similar in their dimensions as shown, some 65 or 70% of the total amount of moisture eliminated from the conditioned air, is eliminated as the air passes from the chamber 11 into the space 13, and the remaining 35-30% of the moisture eliminated, is eliminated from the air as it passes from the chamber 13 into the chamber 15.

For the general purposes of the present invention, the bed material 12 employed, may be any available material having suitable moisture absorption and regenerative capacity. Various known substances other than silica-gel and substances consisting of, or including calcium chloride, are available for such use. At present, I prefer to employ for the purpose, an artificial product comprising a highly porous furnace product matrix material known as micro-porite and calcium chloride lining or deposited the fine pore walls of the matrix material. With the material 12 of such character, and with the dehumidification procedure described, the material 12 will continuously absorb about 70% of the moisture in the air passed into the chamber 11 throughout each dehumidification period of about 40 minutes.

As already indicated, the moisture absorbing action of the material 12 is adiabatic, and the

passage of the air dehumidified through the material 12, increases the temperature of the air in correspondence with the latent heat of evaporation of the moisture absorbed, substantially all of such latent heat being transferred to the air. 5

With the type of evaporative air cooler 22 employed, it is possible to cool the conditioned air down in its passage through the air cooler to within 5° or so of the wet bulb temperature of the air supplied through the inlet 2 to the inlet 10 chamber 5. Thus, with the above assumption of an inlet air temperature of 85° and relative humidity of 70%, it is practical to cool the conditioned air delivered through the outlet 2, to a temperature of about 82° F. 15

For regeneration stage operation, the dampers or valves 17 and 35 are opened, the damper 19 is closed, and the air heating apparatus 9 is set into operation to heat and dry air, which is moved by the blower 6 from the chamber 5 through the conduit 7, and chamber 8 and port 10 into the upper end of the chamber 11 as in the dehumidification stage. Since the chambers 11 and 15 are then in free communication, some of the air entering the chamber 11 will pass downward 25 through the latter into the chamber 15. The air passing into chamber 11 and not entering chamber 15, and the air which does enter the chamber 15, pass in parallel through the respective upper and lower portions of the previous material 12 into the space or chamber 13, which opens at its upper end into a conduit or chamber 36 extending beneath the previously mentioned waste conduit or chamber 33, with which the chamber 36 is in direct communication when the valve or 35 damper 35 is open. As will be apparent with the chambers 11 and 15 similar to one another in their dimensions, appreciably less than one half of the air entering the chamber 11 will pass from the latter into the chamber 15. This is 40 desirable with the described arrangement, in which as already noted, approximately 65 or 70% of the moisture eliminated from the air in the conditioning stage is absorbed by the upper portion of the material 12 surrounding the chamber 11, so 45 that the material 12 surrounding the chamber 11, needs to be subjected to a much greater regeneration effect than does the lower portion of the material 12 surrounding the chamber 15. With the apparatus proportioned as illustrated, no throttling by valve 17 of the port which it controls, is necessary to so proportion the relative amounts of air passing through the portions of material 12, respectively surrounding the chambers 11 and 15, as 50 to subject those portions to appropriate regeneration effects. 55

While the parts of the unit shown in Figs. 1-7 already mentioned, comprise all that are essential to the operation of the unit in the general manner described, said unit comprises automatic control 60 mechanism and numerous special features of construction and arrangement, not previously mentioned but hereinafter described, which are novel, and contribute to the practical merit and utility of the unit. 65

The unit casing 1, as shown, and conveniently, is in the form of a box formed of metal plate sections welded together, and open at its bottom, with the lower edges of its vertical walls adapted to rest on the floor of the cellar furnace room or 70 other room of the building in which the unit is located. It may be lined with any suitable heat insulating material 39. Conveniently, the casing is rounded at one end to conform with the circular outline of the shell 14. The casing may be formed 75

with openings for conduit connections and for access to the mechanism within the casing, and be provided with suitable covers for the latter, as conditions require or make convenient.

5 The apparatus within the casing 1 is supported on a base member 40 in the form of a hollow box formed by metal plates welded together, and forming the walls of the previously mentioned conduit 20. The top wall of the base member is 10 formed with a circular opening at the end of the base member which is rounded to conform with the rounded end of the casing 1. In this opening is secured a ring frame 41 member of angle bar cross section, supporting the shell 14 and the 15 portion of the apparatus within, and associated with that shell.

At its said rounded end, the base member includes an end part 42, which is removable to 20 permit access to the valve 19 and associated valve mechanism parts. At its opposite end, the top wall of the base member is cut away to provide the previously mentioned port 21 through which the conduit 20 opens to the air cooler 22. To provide additional support for the latter, the end 25 wall of the base member proper is reinforced by an external channel bar 43. Associated with the base member 40 are floor engaging leveling screws 44 serving as legs by which the bottom of the base member is held slightly above the floor level.

30 Associated with the base member 40, is an uprising frame structure 45 which includes a horizontal air cooler supporting channel bar 45a, a motor supporting platform 45b, and a channel bar 45c, forming a part of an enclosure for 35 control mechanism terminals, hereinafter described. The uprising frame structure 45 also includes frame parts, other than those mentioned, which do not need to be described, or further referred to herein, as their specific form and arrangement constitutes no part of the present invention, and they may be varied as conditions make desirable.

An electric motor 46 mounted on the platform 45b is employed to drive through a belt 47, a 45 common shaft 48, suitably journaled in the framework of the apparatus, and carrying the impellers of the two previously mentioned fans or blowers, 6 and 31. The latter may be of any known and suitable type and form, and as shown 50 50 are Sirocco blowers.

The pervious wall or bed including the material 12, comprises inner and outer spaced apart screen sections of perforated sheet metal. As shown there are two end to end inner sections 50 and 51, 55 between which a marginal portion of the previously mentioned partition 16 extends to thereby support the upper section 50, and a single outer section 52. Each of the sections 50, 51, 52 is formed with deep groove and rib forming corrugations parallel to the common axis of the chambers 10 and 15. The internal corrugation grooves and ribs of the outer section 52 nest with the corresponding external ribs and grooves of the inner sections, to provide a space for the 60 material 12 which is of substantially uniform thickness and extends in zig-zag fashion about the axis of the chambers 10 and 15. The perforations in the screen sections are preferably very numerous and very small, and in the particular 65 apparatus shown there are nearly two hundred perforations, each about three-sixty-fourths of an inch in diameter, per square inch of screen surface.

The sections 50, 51, and 52 may advantageously 70 be formed of very thin sheet metal, and because

of their thinness and deep corrugations, reinforcing bands 53 are advantageously welded or riveted to the innersides of the inner sections, one adjacent each end of each of the latter, each band 53 being riveted to the crests of the internally extending corrugation ribs of the corresponding screen section. Similar bands 54 are welded or riveted to the crests of the outwardly extending corrugation ribs of the outer section 52, adjacent each end of that section. The bands 10 53 and 54 assist in preserving the proper relative disposition of the different corrugations of the sections, particularly in assembling the apparatus.

The lower edges of the lower inner section 51 15 and the outer section 52 rest on an annular bed plate 55, which, in turn, rests upon and is supported by the annular base member part 41. The previously mentioned port 18 is in the form of a central opening in the bed plate 55. The top 20 end of the upper section 50 is shown as spaced from the outer section 52 by clips 56.

The previously mentioned inlet port 10 to the chamber 11 is formed in a platelike part 57 which rests on the upper ends of the screen sections 50 25 and 52, and is provided at its periphery with a depending skirt or cylindrical extension part 58. The latter forms the upper portion of the previously mentioned shell 14, or outer wall for the space 13. The shell 14 comprises a cylindrical 30 body portion in telescoping relation at its upper end with the skirt or cylindrical part 58, and at its lower end with a cylindrical part 59 which rests upon the bed plate 55. In the assembled apparatus, the upper end portion 58 of the wall or 35 shell 14 is anchored to the bed plate 55 by tie-rods 60, which advantageously include bends to permit of sufficient elongation and contraction in length of the tie-rods to accommodate the elongation and contraction of the screen sections, 50, 40 51, and 52, as the latter heat up in the regeneration stage, and cool down in the dehumidification stage, of each cycle. As shown, the tie-rods 60 pass at their lower ends through apertures formed in the bed plate 55 and have their upper 45 ends passing through lug or ear parts 61 welded on the top member or skirt part 58.

The air heating apparatus 9 in the chamber 8 as shown is directly supported by the plate part 57 and comprises parts novel in their construction and 50 arrangement, peculiarly adapting the heating apparatus to its intended use. Said parts include a multiplicity of similar vertically disposed burner elements 70, arranged in a circular series about the common axis of the port 10 and chambers 11 55 and 15. Each element 70 includes a chamber 71 receiving fuel gas mixed with primary air, through a passage 72 axially disposed in a nipple extension 73 of the element at its top. In the inner wall of each chamber 71 is formed a multiplicity of burner orifices 74 directed toward the center of the cylindrical space surrounded by the series of elements 70. The elements 70 comprise portions extending outwardly beyond the corresponding chambers 71 and curved so that each 60 element forms a vane cooperating with each adjacent element to form a curved nozzle or air inlet passage 75 between each pair of elements 70, which leads horizontally inward from the space at the outer sides of the elements 70, into the 70 cylindrical space surrounded by those elements.

The vertical wall 76 of the chamber 8, as is clearly shown in Fig. 5, is shaped to give the portion of the chamber 8 between it and the element 70, the form of a scroll or spiral space, di- 75

minishing in cross section as the angular distance about the axis of the chambers 11 and 15, from the intersection of the conduit 7 with the chamber 8 increases. The curvature of the 5 passages 75 is such that the outer ends of those passages approach a tangential relation with cylindrical inner side of said scroll space, and face the direction of flow from the conduit 7 through said scroll space. In consequence, as 10 those skilled in the art will understand, the air entering the scroll space from the conduit 7, passes from that space into the cylindrical space surrounded by the burner elements 70, with a desirable uniformity of distribution of flow 15 among, and small loss of pressure head in, the different passages 75, so as to insure the effective use of each of the different burner elements, and the maximum air heating effectiveness, therefore, of those elements.

20 As shown, the burner elements rest upon and are supported by the horizontal plate part 58, at the margin of the port 10, being spaced by spacer parts 71 carried by the plate 57. The nipple extensions 73 at the tops of the burner 25 elements are externally tapered, and are snugly received in tapered apertures in a superposed manifold element. The latter, as shown, comprises four quadrantal arc shaped hollow bodies 78, bolted together at their ends to form a rigid 30 annular element. Each manifold quadrant 78 receives fuel gas mixed with primary air for combustion, through a Venturi tube shaped tubular member 79, providing a mixing passage similar in form and effect to the characteristic mixing 35 passage of an ordinary Bunsen burner. Each member 79 receives fuel gas through a nozzle part 80 extending axially into the inner end of the member and forming the delivery end of a corresponding pipe branch 81 from a primary gas 40 supply manifold 82 of cruciform shape, including one arm for and supplying gas to each of the mixing members 79. The primary manifold 82 receives gas through a supply pipe 83 including a control valve 84 automatically actuated as hereinafter described. Primary air is aspirated into 45 the inlet end of each mixing member 79, through air inlet ports 85 in apertured diaphragm plates 86 surrounding the corresponding gas nozzle 80, and adapted for adjustment in a manner commonly employed in Bunsen burner mixers. The burner elements 70 have hollow vane tip portions and their light weight, coupled with their relatively large heat dissipating surfaces, permits of a suitably large heating capacity with such small 50 heat storage capacity that their significant air heating effect ceases almost immediately when their fuel gas supply is interrupted.

The gas supply control valve 84 and the gas burning parts above the burner element 70, are 55 located in an uprising extension from the chamber 8, which is surrounded by a cylindrical casting element 87. The latter extends upwardly through the top wall of the housing 1, and is closed at its upper end by a cover 88, removable 60 to permit access to the air heating apparatus. The cover 88 is formed with a vent opening 89 normally closed by a light weight disk valve 90, which is moved upward into vent closing position by the pressure of the air in the chamber 8, 65 when that chamber is receiving air from the fan 6 during the dehumidification and regeneration stages in normal operation. When the operation of the fan 6 is interrupted, as it may be during certain hours of the day, or other periods in which 70 operation of the apparatus is temporarily un-

necessary, the disk valve 90 drops and opens the vent 89. The latter is provided primarily to permit the escape of products of combustion produced by a pilot burner 91, when the latter is left in operation during periods in which the operation of the blower 6 is temporarily interrupted. 5 The purpose of the pilot burner is to ignite the gas and primary air mixture discharged through the burner element ports 74, when the gas supply valve 84 is opened at the beginning of each 10 regeneration stage. The pilot burner receives gas through a supply pipe 92, separate from the pipe 83 and not controlled by the main gas supply valve 84.

The air cooler 22, as shown, is formed by 15 vertically disposed plates 100 and 101, which as assembled are right and left hand counterparts of each other, and which alternate in the assembled group of plates which are held in contact with one another. The plates 100 and 101 as 20 shown, are actually identical in form but are reversely arranged. Each plate 100 is formed at one side with a series of vertical ribs 102 and which may be regarded as forming the sides of corresponding vertical grooves, the width of each 25 of which is appreciably greater than the width of each rib 102. The ribs 102 of each plate 100 extend centrally into the said grooves of the immediately adjacent counterpart plate 101, and the ribs 102 of the last mentioned plate extending 30 centrally into the grooves between the ribs 102 of the first mentioned plate, as is clearly shown in Figs. 3 and 4. The opposing grooves of each plate 100 and its counterpart plate 101 at the right, as seen in Figs. 3 and 4 collectively form 35 one of the cooler channels 23 for the dehumidified air. Each such channel, zig zag in horizontal cross section as clearly shown in Fig. 4, extends for nearly the full width of the cooler in the direction of the plates 100 and 101. As previously 40 stated, each channel 23 opens at its lower or inlet end to the outlet part 21 of the conduit 20 and opens at its upper end to the conditioned air outlet part 3 of the casing 1.

At the sides of the plates 100 and 101 opposite 45 to those carrying the ribs 102, each plate is formed with a groove extending for nearly the full width of the plate. Said groove in each plate 100 and the opposing groove in the plate 101 to the left, as seen in Figs. 3 and 4, collectively form one of 50 the previously mentioned cooling agent channels 24. Each of the said grooves thus forming a part of a channel 24 has an upper end portion 103 closed at its upper side and extending horizontally to the right hand edge of the corresponding plate as seen in Fig. 1, and increasing in depth 55 as it approaches that edge. The opposing groove portions 103 thus unite to form an enlarged inlet portion for the corresponding channel 24 which opens directly to the outlet 28 of the spray chamber 26. At the bottom of the cooler, the opposing grooves forming each channel 24 are laterally extended to provide a horizontal outlet portion of the channel 24 which tapers in width and opens directly to the inlet end of the conduit 27. 60

The plates 100 and 101 forming the laminated cooler 22 are clamped together by suitably disposed tiebolts 105. As shown, each plate 100 and 101 is formed with dovetail tenon extensions 106 at its opposite edges and intermediate their 70 ends, and one tenon of each plate is snugly received in the previously mentioned channel bar framework portion 45a. In practice, provisions, which may be of any suitable or known character and hence need not be described in detail, 75

are provided to seal the joints between the plates 100 and 101, adjacent the edges of the cooler. As will be apparent also, suitable provisions are needed to prevent leakage between the plenum space 5 within the casing and the joints between the cooler and the conduit 20 and outlet 3. As will be apparent also, suitable provisions should be made for sealing the joint between the lower portion of the casing or shell 14 and the conduit 20, since in operation, the air pressure in the flow paths, through which air is passed by the fan 6, to the dehumidified air outlet 3 and the waste outlet 4, is above the pressure of the atmosphere prevailing in the space 5. In the portion of the cooling agent flow path, at the inlet side of the port 31, the pressure will be lower than the pressure of the atmosphere and suitable provisions are necessary to prevent any leakage of air from the space 5 into that flow path portion. The leakage preventing provisions need not be further described or further referred to however, as those skilled in the art will understand how to provide suitable provisions for the purpose.

The nozzles 27 in the spray chamber 26 discharge jets of water downward against a deflecting target member 110 located in the spray box 26 adjacent the inlet 25 thereto. The target member breaks up or atomizes the water in the jets impinging against it and the water thus broken up, is deflected by the target away from the latter in the form of a mist moving in the general direction of the air stream passing through the spray box inlet 25 to its outlet 28 and into which stream, the water mist is dispersed. In the unit illustrated, a drain pipe 110a is provided for the discharge of unevaporated spray water carried into and collecting on the floor of the conduit 29.

As shown, the valve or damper members 17 and 19 are connected to a common vertical operating spindle 115, which is engaged at its lower end by a lever pivoted at 117 in a bracket carried by a beam or bar 118. The latter extends chord-like across a portion of the member 41 at one side of the port 18, and may be welded at its ends to the depending vertical flange portion of the member 41. The end of the lever 116 remote from the valve spindle 116, is connected to the lower end of a vertically movable spindle or rod 120, which is connected at its upper end to, and carries and operates the damper 35. When the rod 120 occupies its upper position, shown in Fig. 1, the valve member 17 closes the port in the partition 16, the valve member 19 opens the port 18, and the valve member 35 closes the port between the waste conduit or chamber 33 and the conduit or chamber 35, which communicates with the space 13. When the valve spindle 120 is lowered from its position shown in Fig. 1, the valves 35 and 17 are moved to their open positions and the valve 19 is moved to its closed position.

The valve rod 120 is periodically moved between its upper and lower position by means of a crank arm 121 angularly adjusted by a periodically operating electric damper motor 122. As shown, the crank arm 121 is connected to the rod 120 at points respectively above and below the crank arm by means of upper and lower springs 123 and 124 respectively. The lower spring 124 is put under tension to insure snug engagement of the valve members 17 and 35 with their respective seats, when those valves are moved into their closed positions, and the upper

spring 123 is put under tension to insure snug engagement with its seat of the valve member 19 when the latter is moved to its closed position, without jamming or causing any of the valve members to push or bear with undue pressure against its seat.

In Fig. 1, I have diagrammatically illustrated an automatic control system, which may be employed to automatically operate the apparatus unit shown in Figs. 1-7, as required for recurring dehumidification operations and alternating activation or regeneration operations at suitable intervals, and which also includes safety provisions for preventing operation of the apparatus in the event of one or more contingencies making the continued operation of the apparatus unsafe or undesirable. In Fig. 9, 130 and 131 represent electric current supply conductors, supplying energy for the operation of the previously mentioned fan and damper operating motors 46 and 122, and for energizing control elements as hereinafter described, through terminals carried by a terminal board 132. The latter is conveniently located in a space 132, the enclosing wall of which is formed in part by the previously mentioned channel bar frame part 45c.

A main terminal 130a of the terminal board 132, is directly connected to the supply conductor 130. The cooperating main terminal 131a is connected to the conductor 131 by a branch conductor 134 and switch element 135, only when the latter is held in its closed position, by the energization of a coil 136. Conveniently, and as shown, the coil 136 is energized by the low voltage current in the secondary circuit 137 of a step down transformer 137a, having its primary winding connected across the supply conductors 130 and 131. The secondary circuit 137 may be closed to energize the coil 136, by the adjustment into its closed position of either of two movable switch elements 138 and 139. The switch element 138 may be a so called owner's switch, manually adjustable by the attendant in charge of the operation of the apparatus, or it may be a humidostat, automatically moving the switch member 138 into and out of its closed position, as the humidity in some room supplied with conditioned air by the apparatus rises to, or falls below a predetermined value.

The switch element 139 is automatically actuated by an electric clock 140, which, as hereinafter explained, is operative to directly determine the duration of each dehumidification stage. As diagrammatically shown, the switch element 139 is an arm carried by a shaft rotated by the clock 140, to thereby move the arm 139 into and out of engagement with a contact 141 once for each complete operative cycle of the apparatus. As hereinafter explained, the clock control switch 139 is provided to prevent interruption of the operation of the apparatus, by an opening adjustment of the switch element 138 at a time when the bed of moisture absorbing material 12, is in the wet condition normally prevailing at the end of each dehumidification stage. The contact 141 is elongated and disposed so as to be in engagement with the switch element 139 for a couple of minutes or so prior to the hereinafter described interruption of the clock-movement occurring at the end of each dehumidification period.

The terminals of the fan or blower motor 46 are connected by conductors 142 to the terminals 130a and 131a, so that the motor 46 is energized, so long as the coil 136 is energized. The termi-

nals 130a and 131a are connected to conductors 143 and 144, respectively, which supply current for energizing the damper motor 122, but the latter is a reversible motor, which is operatively energized only when a switch element 145 is adjusted to connect a common motor control conductor 146 to one, or to the other, of two other control conductors 147 and 148. The switch element 145 forms a part of the clock or timing mechanism 140, and is given one complete rotation, effected in two steps, for each operating cycle of the dehumidifying unit. When the switch member 145 connects the conductors 146 and 147, the motor 122 is operated to give the half turn to the motor crank arm 121, required to shift the valves or dampers 17 and 35 to their open positions, and the damper 19 to its closed position. The motor 122 then de-energizes itself, and is re-energized to give the arm 121 a reverse half turn, thereby opening the damper 19 and closing the dampers 17 and 35, when the clock mechanism moves the switch element 145, into position to connect motor control conductors 146 and 148. The motor 122 may be, and as indicated is, of a well known commercial type, including a limit switch mechanism, which because it is well known need not be described herein, whereby the motor automatically de-energizes itself at the end of each of its movements giving the arm 121 a half turn in one direction or the other.

In the control system shown in Fig. 9, the operation of the clock 140, while determining the duration of each dehumidification period, is intermittently in operation, and does not control the duration of the activation or regeneration periods. The energizing circuit connection for the clock 140, includes an energizing conductor 149 directly connected to the terminal 130a, and a cooperating energizing conductor 150 intermittently connected to, and disconnected from the terminal 131a, at intervals controlled and determined by two switch mechanisms. One of those mechanisms includes a switch arm 151 adjusted by the damper motor 122 on each operation of the latter, and the second mechanism, 152, is automatically responsive to the temperature in the waste air outlet 4 of the unit, or in the exhaust or stack connection leading away from that outlet.

During each period in which the adjustment position of the motor 122 and its crank arm 121, is such as to hold the damper 19 open, and the dampers 17 and 35 closed, as required for dehumidification, the clock 140 is energized by a circuit closed by the switch arm 151, and not controlled by the switch mechanism 152. The clock energizing circuit then closed includes the energized terminal 130a, conductors 149 and 150, energized terminal 150a, of terminal board 132, conductor 153, switch arm 151, conductor 154 and 144, and energized terminal 131a. The clock energizing circuit just described is broken, and the clock operation interrupted, by the movement of switch arm 151 out of operative connection with the conductor 153, effected when the motor 122 is energized by movement of clock switch arm 145 to close damper 19 and open dampers 17 and 35, for regenerative air flow through the material 12.

That operation of the motor 122 moves the switch arm 151 out of its previously maintained engagement with the switch contact connected to the conductor 153, and opens the previously described clock energizing circuit, and the operation of the clock then ceases until a second clock

energizing circuit is established by the operation of the switch mechanism 152. The latter may be of the commercial form manufactured by the Detroit Lubricator Company and designated "Control switch—No. 250 Type MH-2", and operates to adjust the switch arm 155 with a snap action from its left hand, full line position, into its right hand, dotted line position shown in Fig. 9, or from said dotted line, into said full line position, accordingly, as the waste air temperature 10 attains or is below a predetermined temperature, which normally is within a range of 250 to 300° F. That temperature is attained in the normal operation of the dehumidifying unit illustrated, when, and only when, the material 12 is adequately regenerated or activated. During, and prior to the completion of, the desired activation operation, the moisture given up by the material 12 to the regenerating air cools the latter, so that it reaches the outlet 4 at a temperature below 20 that required for the movement of the switch arm 155 into its dotted line position.

The said second clock energizing circuit closed by the movement of the switch arm 155, into its dotted line position, includes conductors 149 and 25 150, a conductor 156 connecting contact 150a, to a stationary contact of switch mechanism 152 then engaged by switch arm 155, a conductor 157 connecting arm 155 to a terminal 158, of terminal board 132, a conductor 159 connecting terminal 158 to a stationary contact of the damper motor switch mechanism, said stationary contact being then engaged by the switch arm 151 and thereby connected to conductor 144.

Following the closure of the energizing circuit just described, the clock 140 starts into operation, and runs during a short purging period of three minutes or so, before the resultant movement of the clock switch arm 145 brings the latter into circuit relation with the control conductor 148, 40 and thereby actuates the motor 122 to adjust the dampers 17, 19, and 35 into their dehumidifying positions and initiate the following dehumidification stage. The last mentioned operation of motor 122, moves the switch arm 151 out of connection with conductor 159, thereby breaking the second mentioned clock energizing circuit, but moves the arm 151 into circuit relation with the conductor 154, thus immediately restoring the first mentioned energizing circuit for the clock 50 140, which thereafter runs continuously until the last mentioned dehumidification stage is completed.

During the above mentioned purging period, which may be regarded as a final portion of the 55 regeneration period, the main gas valve 84 is closed, and the air then passing to the waste air outlet through the material 12, subjects the latter to a substantial cooling action, desirable prior to use of the material in the following dehumidification stage.

With the control system shown in Fig. 9, the operation of the main gas valve 84 is electrically controlled, and the valve can be moved into and maintained in its open position only 65 during a period in which the dampers 17, 19, and 35 are not only adjusted for regenerative action, but in which the waste air temperature is suitably low, and then only if there is a pilot burner flame, and if the air heater temperature is 70 not abnormally high.

The valve 84 illustrated, is a so called motorized valve of known type including an electric motor 160, the energization and deenergization of which opens and closes the valve 84. The 75

motor 160 is connected in the secondary circuit 161 of a transformer 162. The primary winding 163 of the transformer is included in a circuit which is energized only when the switch arm 155 of switch mechanism 152 is in its low temperature, full line position, and the switch arm 151 is in the position occupied when the dampers 17 and 35 are open and the damper 19 is closed. With the switch arms 155 and 151 in said positions, the primary winding 163 is connected between the energized terminals 130a and 131a, in series with a terminal 164 of terminal board 132, conductor 165, switch arm 155, conductor 157, terminal 158, conductor 159, switch arm 151, conductor 154 and conductor 144.

The secondary transformer circuit 161 includes in series with the motor 160, a fusible link 166, and a switch 167 associated with a valve 168 in the pilot valve supply pipe 92, and controlled by a device 169 responsive to the heat of the flame from the pilot burner 91.

The fusible link 166 is located in the upper burner extension of the chamber 8, so as to be subject to the temperature therein, and is adapted to give way and open the transformer circuit 161, and thereby effect the closure of the main gas valve 84, when said temperature rises above normal, as it would on interruption of the flow of regeneration air through the chamber 8. Such air flow interruption might result from the breakage of the fan belt 47, or from the development of some condition, other than the failure of the supply current, making the fan motor 46 inoperative. The fusible link is not necessary to protect the apparatus against an interruption of the current supply by conductors 130 and 131, since that interruption would deenergize the solenoid 136 and permit the switch 185 to open under its spring bias and thereby effect the closure of the main gas valve 84.

The opening of switch 167 opens the secondary circuit 161, and thereby closes the main gas valve 84 if previously open. The switch 167 is held in its closed position by the device 169, when the latter is subjected to the heating action of the normally continuously burning pilot burner flame. In case of the accidental extinction of that flame, the device 169 permits or effects the opening of the switch 167. The device 169 may be any suitable thermally responsive device, but advantageously, is of a known commercial form, including the hot junction of a thermo-couple having its leads, enclosed by a couple 170, connected to an electric magnetic device 171, which is actuated by the thermo-couple current due to the heating effect of the pilot burner flame, to maintain the switch 167 in its closed position. Advantageously also, the device 171 is associated with the valve 168 so as to effect the closure of the latter, and thereby interrupt the gas flow to the pilot burner, when its flame is extinguished. The mechanical details through which the energization and deenergization of the electromagnetic device 171 result in the opening and closing, respectively, of the valve 168, form no part of the present invention, and hence need not be further described or referred to herein.

In the contemplated normal operation of the unit illustrated, as will be apparent from what has already been said, the fan or blower 6 moves air continuously into contact with the material 12 during the successive dehumidification and regeneration stages or periods. During each dehumidifying period, the air flows downward through a flowpath portion including the cham-

bers 11, 13, and 15, and then flows upward through the flowpath portion formed by the air cooler passages 23, and during each regeneration period, the air flows downward through the chambers 11 and 15 and upward through the chamber 13, the flowpath in each case being U shaped.

In the contemplated normal operation of the unit, the fan 31 moves air through the air cooler passages 24 and the nozzles 27 supply water to the spray chamber, during the activation periods, as well as during the dehumidification periods. The resultant subjection of the air cooler to a cooling action during the dehumidification periods, would be unnecessary with other air coolers which may be employed in some cases, but is desirable with the evaporative air cooler illustrated, because of the considerable heat storage capacity of the latter. In consequence, of that heat storage capacity, the cooling action to which the cooler is subjected during the regeneration periods, is advantageous because it results in a lower average cooler temperature during the dehumidification periods than would otherwise prevail, and thereby increases the effective cooling capacity of the cooler.

While general principles of the invention disclosed may be utilized in apparatus differing widely in form from that disclosed, the particular unit construction and arrangement illustrated possesses important practical advantages for the use of the unit in the cellar, basement, or analogous furnace room, of a dwelling house of moderate size.

For that use, the inherent compactness of the unit illustrated, and the location of the air inlet and air outlets at the top of the unit, are of practical importance. The unit illustrated may be generally similar in bulk, and in its space requirements, to an ordinary house heating furnace such as would ordinarily be installed in the same furnace room of a dwelling house in which the improved air heating unit is located. For such use, the location of the air inlet 2 and air outlets 3 and 4 at the top of the unit is practically convenient and desirable because of the resultant disposition permitted of the associated air conduits. For the normal contemplated use of the unit, the conditioned air outlet 3 must be connected to a conduit system through which the conditioned air is passed to the room or rooms in which that air is used, and in practically all cases, the waste air outlet 4 should be connected to a conduit leading to a stack or otherwise arranged for the discharge of the waste air into the outside atmosphere. While in some cases, the inlet 2 may open directly into the room in which the unit is located, it is generally desirable to provide a fresh air conduit leading to the inlet 2 from the outside atmosphere. The air conduits required are of substantial cross sectional area and flow capacity, since the amount of air conditioned is desirably much in excess of the amount of fresh air needed to satisfy the standard minimum fresh air ventilation requirements of the rooms in which the conditioned air is used for conditioning, as well as for purely ventilation purposes.

A disposition of the moisture absorbing material 12 relative to the air flow provisions, permitting of the movement of the air to be dehumidified into series contact with the different portions of the moisture absorbing material, and the passage of the heated activating air in parallel streams into contact with said portions, contrib-

utes both to the compactness of the unit and to the desirable rapidity with which each activation operation may be effected. As will be apparent, the series and parallel movements of the air into contact with the material 12 during the dehumidification and activation periods, respectively, may be effected with apparatus very different in form from that illustrated, but the arrangement of the material 12 in a wall or bed in the form of a corrugated cylinder and in conjunction with valves or dampers and flowpath provisions as illustrated in the drawings, permits of the attainment of the series parallel flow of air into contact with the material, in apparatus which is compact, and in which the extent of absorbing material bed area in a direction transverse to the air flow, is relatively large.

In the unit arrangement illustrated, the utilization of practically the entire vertical height of the unit to accommodate the dehumidifying section of the apparatus and the necessary inlet and outlet flowpath provisions associated therewith, contributes to the compactness of the unit, and permits the air heating apparatus to be located at the top of the unit, as is practically convenient and desirable, without necessarily increasing the vertical dimensions of the unit except for a slight vertical elongation of the inlet air flowpath portion formed by the chamber 8, and for the provision of the space to accommodate the burner gas supply connections.

The air heating apparatus illustrated has certain special advantages for use as an air heater, particularly, with the gas and air pressure conditions prevailing with the intended normal use of the unit illustrated. For that use, it is desirable that the conditioned air should be supplied to the rooms to be conditioned at a pressure slightly in excess of atmospheric pressure, so as to minimize the infiltration of atmospheric air into those rooms. As is well known to those skilled in the art, in an ordinary moderate sized dwelling house of normal construction and with a moderate summer wind velocity of 15 miles per hour, the amount of atmospheric air entering the house through leaky windows and other joints, is ordinarily assumed to be that required for a complete change of air in the house in some 30 to 45 minutes. Such a considerable infiltration of atmospheric air into rooms would materially reduce the sought for advantage of supplying dehumidified air to the rooms. By supplying the conditioned air at a pressure slightly above that of the atmosphere, the otherwise normal amount of atmospheric air infiltration may be materially reduced.

When air to be conditioned is supplied under pressure to the chamber 8 as provided for in the particular unit construction illustrated, the air pressure in the chamber 8 may well be above the atmospheric pressure, by an amount corresponding to about one and a half inches of water. The ordinary domestic valve gas supply pressure may be expected to normally exceed the atmospheric pressure by an amount corresponding to about two and a half inches of water. As will be apparent, the arrangement of the burner elements to provide the special nozzle shaped flow passages 75 for the air passing into the combustion space surrounded by the burner elements 10, is of advantage in securing the required relatively large amount of gas flow through the ports 14, notwithstanding the small excess of the gas pressure over the pressure of the air admitted to the chamber 8. With the described nozzle arrangement, the high velocity of the air streams dis-

charged from the nozzle passages at opposite sides of each burner element, and in close proximity to the corresponding ports 14, significantly reduces the pressure at the outlet ends of said ports. In effect, the gas passing through those ports, is subjected to an aspirating action by the adjacent air streams. In my copending application Ser. No. 155,403, filed July 24, 1937, I disclose other forms of apparatus for accomplishing the general purposes of, and obtaining advantages obtainable with, the apparatus disclosed herein, and in said application, Serial No. 155,403, I am generically claiming features of invention disclosed in common in the last mentioned application and herein.

As will be apparent to those skilled in the art, changes may be made in the form of the apparatus illustrated and described herein without departing from the spirit of my invention as set forth in the appended claims, and in some cases use may advantageously be made of certain features of my invention without a corresponding use of other features.

Having now described my invention, what I claim as new and desire to secure by Letters Patent, is:

1. Regenerative dehumidifying means comprising a pervious wall including moisture absorbing material and surrounding a space, valved partition means operable to open and close full communication between opposite end portions of said space, means defining an enclosed space surrounding said pervious wall, means operable to supply air to be dehumidified to one of said end portions and to withdraw dehumidified air from the other end portions when said portions are not in free communication, means for supplying heated air to one of said end portions and thereby to the other when the two end portions are in free communication, and means for withdrawing air from said surrounding space.

2. Regenerative dehumidifying means comprising inner and outer screen walls in the form of corrugated spaced apart cylinders with the corrugation ribs and grooves of each wall extending parallel to the axis of the cylinders and nesting with the corrugation grooves and ribs of the other cylinder, moisture absorbing material in the space between the shells, means defining an enclosed space surrounding the outer screen wall, valved partition means within the inner screen wall operable to open or close direct communication between opposite end portions of the space surrounded by the inner screen wall means for passing air into one of said end portions, means adjustable to pass air either from the opposite end portion or from said enclosing space, and air heating means operable to heat the air entering the first mentioned space when said end portions are in direct communication.

3. Regenerative dehumidifying means, comprising a pervious wall including moisture absorbing material surrounding a space, valve means in said space alternately operable to establish and to interrupt communication between opposite end portions of said space, casing means providing a second space surrounding said wall, and having an air outlet, intermittently operable air heating means, means operable to move air past said heating means into one of said end portions, the second of said end portions having an air outlet, valve means operable to permit or prevent the outflow of air from said second end portion through its said outlet, valve means controlling the outlet from said second space, and a common

- operating means for the three valve means operable to adjust the latter for airflow from said one end portion through said wall into said second space and thence through said wall into said second end portion and thence through the second mentioned outlet, and for airflow from the first mentioned end portion directly into the other end portion and from each of said end portions through said wall into said second space and thence through the first mentioned outlet.
4. Regenerative dehumidifying means comprising a pervious wall including moisture absorbing material surrounding a space, means in said space alternately operable to establish and to interrupt direct communication between opposite end portions of said space, means operable when said communication is interrupted to pass air to be dehumidified into one of said end portions, thence outwardly through the portion of said wall surrounding said one end portion and thence back into the other end portion through the portion of said wall surrounding the last mentioned end portion, and means operable when said communication is established to pass heated air into both of said end portions and thence outwardly from each of the latter through the portions of said wall respectively surrounding said end portions.
5. In dehumidifying apparatus comprising material adapted when activated, to absorb moisture from air in contact therewith and to be reactivated by contact with the air when the latter is heated, a chamber through which air normally passes into contact with said material at a pressure above that of the atmosphere, a gas burning air heater in said chamber, fuel gas supply means adjustable to supply fuel gas to said heater during reactivation periods and to interrupt the supply of fuel gas to the heater during dehumidification periods, a pilot burner in said chamber, said chamber having a vent to the atmosphere, and pressure responsive valve means controlling said vent and closing the latter when the pressure in said chamber is in excess of atmospheric pressure and opening said vent when the pressure in said chamber diminishes, whereby the products of combustion formed by the operation of the pilot burner may be discharged through said vent when the normal air flow through said chamber is interrupted.
6. In dehumidifying apparatus comprising material adapted when activated to absorb moisture from air in contact therewith and to be reactivated by contact with the air when the latter is heated, a chamber through which air normally passes into contact with said material at a pressure above that of the atmosphere, a gas burning air heater in said chamber, fuel gas supply means adjustable to supply fuel gas to said heater during reactivation periods and to interrupt the supply of fuel gas to the heater during dehumidification periods, a pilot burner in said chamber, said chamber having a vent to the atmosphere, pressure responsive valve means controlling said vent and closing the latter when the pressure in said chamber is in excess of atmospheric pressure and opening said vent when the pressure in said chamber diminishes, whereby the products of combustion formed by the operation of the pilot burner may be discharged through said vent when the normal air flow through said chamber is interrupted, and means responsive to the temperature to which the air is heated by said heater for interrupting the fuel gas supply thereto when

said temperature exceeds a predetermined amount.

7. Apparatus for conditioning the air for room spaces comprising a body of material capable when activated of absorbing moisture from a stream of air passing thereover, and adapted to be reactivated by giving up previously absorbed moisture to a relatively warm air stream passing thereover; conduit means providing for the passage of air over said material and into the room space; means for moving air over said material and through said conduit means into the room space; means for periodically heating the air flowing to said material; means operable simultaneously with said heating means for diverting the warm air from said conduit means; timing mechanism operable to effect the flow of air over said material and through said conduit means and into the room spaces for dehumidifying periods of fixed duration, and for rendering said heating means and air diverting means operative at the end of each dehumidifying period; and means responsive to a characteristic reflecting the moisture content of said material for rendering the heating means and air diverting means inoperative and the timing mechanism operative.

8. The method of conditioning the air in room spaces which comprises moving air at its prevailing temperature through a body of material, adapted when activated to abstract moisture from the air, for intermittent dehumidifying flow periods of equal and relatively long duration; establishing a flow path for such dehumidified air as it leaves said body of material which path leads to the space to be conditioned and lowering the dry bulb temperature of such air as it traverses such flow path; moving reactivating air through said body of material for substantially the entire duration of each of the intervals between dehumidifying flow periods to provide reactivating periods alternating with the dehumidifying flow periods, with the reactivating periods being of relatively shorter duration than the dehumidifying flow periods and being of lengths respectively dependent upon a characteristic reflecting the moisture content of said body of material; heating the reactivating air prior to contact with said body of material for at least a substantial portion of each reactivating period; and diverting the reactivating air from said flow path.

9. A method as specified in claim 8 wherein the characteristic reflecting the moisture content of the material is measured by the temperature of the reactivating air leaving the material and wherein the reactivating periods are terminated in response to a predetermined temperature of the outgoing air indicating that the material is substantially free of moisture.

10. A method as specified in claim 8 wherein each dehumidifying period is of the order of 40 minutes and wherein the duration of each reactivating period is of the order of 13 to 20 minutes.

11. A method as specified in claim 8 wherein all of the air moving over the moisture absorbing material is taken from a common source and moves along a single flow path leading to the material.

12. A method as specified in claim 8 wherein the air flows in series through different portions of the moisture absorbing material during dehumidifying periods and through such portions in parallel during reactivating periods.
